(57) **CLAIM**

The ornamental design for a curtain rod assembly, as shown and described.

DESCRIPTION

FIG. 1 is a front perspective view of a curtain rod assembly, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof shown assembled in an alternative configuration of use.

FIG. 10 is an enlarged detail view of area 10 in FIG. 1;

FIG. 11 is an enlarged detail view of area 11 in FIG. 1;

FIG. 12 is an enlarged detail view of area 12 in FIG. 1;

FIG. 13 is an enlarged detail view of area 13 in FIG. 5; and, FIG. 14 is an enlarged detail view of area 14 in FIG. 9.

The broken lines in the drawings illustrate the portions of the curtain rod assembly, which form no part of the claimed design.

The dash-dot-dash broken lines surrounding the detail views shown in FIGS. 1, 5 and 9-13 are for purposes of annotating the enlarged view only and form no part of the claimed design.

1 Claim, 14 Drawing Sheets
